No. 802,116.

PATENTED OCT. 17, 1905.

J. G. ROSEBOOM.
SASH FRAME AND SASH.
APPLICATION FILED MAR. 16, 1905.

UNITED STATES PATENT OFFICE.

JESSE G. ROSEBOOM, OF CINCINNATI, OHIO.

SASH-FRAME AND SASH.

No. 802,116.

Specification of Letters Patent.

Patented Oct. 17, 1905.

Application filed March 16, 1905. Serial No. 250,392.

To all whom it may concern:

Be it known that I, JESSE G. ROSEBOOM, a citizen of the United States, residing at Cincinnati, in the county of Hamilton and State 5 of Ohio, have invented new and useful Improvements in Sash-Frames and Sashes, of which the following is a specification.

My invention pertains to sash-frames and sashes; and it has for one of its objects to provide 10 a construction which is effectual in excluding the wind and weather and yet is adapted to permit the sash to both slide and swing.

Another object of the invention is the provision 15 of a sash embodying such a construction that a pane of glass may be expeditiously and securely fastened therein without resort to the use of putty or the like and in such manner that the pane of glass may be readily removed when broken and as readily replaced with a new pane.

Other objects and advantages of the invention will be fully understood from the following description and claims, when taken in 20 connection with the accompanying drawings, forming part of this specification, in which—

Figure 1 is a front elevation illustrating a sash-frame and sashes constructed in accordance with my invention. Fig. 2 is an enlarged section taken in the plane indicated by the line 2 2 of Fig. 1. Fig. 3 is a detail view of one of the vertically-movable slide-bars comprised in my improvements. Fig. 4 is a similar view of one of the wind-guards used 30 in connection with the slide-bars. Fig. 5 is an enlarged detail horizontal section illustrating the relative arrangement of the pane of glass, the glass-holder, and the adjacent bar of the sash precedent to placing and securing the 35 glass in the sash.

Similar letters designate corresponding parts in all of the views of the drawings, referring to which—

A A are the side stiles of my novel sash-frame. These stiles are preferably, though not essentially, formed of sheet metal and respectively comprise parallel ways *a* and compartments *b*, arranged back of the ways *a* and separated therefrom by partition-walls *c*.

B B are vertically-movable slide-bars arranged in the ways *a* and against the wall *c* and having cams *d* on their outer faces.

C C are weights movable vertically in the compartments *b* of the stiles, and D D are 55 cables connecting the slide-bars B and the weights C and passed over sheaves *e*, mounted

at the upper ends of the partition-walls *c*, as best shown in Fig. 1. In virtue of this construction it will be observed that the weights will be raised by the downward movements 60 of the slide-bars B and will assist in the upward movements of the said slide-bars for a purpose presently set forth.

E are wind-guards, of which there is one complementary to each way *a* of the side stiles. The said wind-guards E are preferably of sheet metal and are provided with cams *d'*, complementary to the cams *d*, and are also provided with finger-pieces *f* and vertical slots *f'*. When the wind-guards E are 65 moved through the medium of their finger-pieces *f* or other means in one direction, the cams *d'* of said guards, moving against the cams *d* of the slide-bars B, will permit the guards to move laterally toward the bars B, 70 while when the guards are moved in the opposite direction the cams *d'*, acting against the cams *d*, will move the guards laterally inward or away from the bars B.

G G are pins fixedly connected to the slide-bars and extending through the slots *f'* of the wind-guards E and laterally inward beyond the wind-guards, and H H are my improved sashes, the side bars of which are mounted on the pins G, whereby the sashes 80 are adapted to swing. In their outer edges the side bars of the sashes (which side bars are lettered *g*) are provided with grooves *h* to receive the outer portions of the wind-guards E after the manner shown in Fig. 2. 85 From this it follows that when the wind-guards are in their normal positions they will prevent the passage of wind and weather between the side stiles of the frame and the adjacent bars of the sashes. It will also be observed that when the parts are in the relative 90 positions shown in Fig. 2 and one of the sashes is raised—the lower sash, for instance—the said sash, its complementary wind-guards, and its complementary slide-bars will 95 move upwardly together, and such movement will be assisted by the counterbalance-weights, before described, while when the sash is lowered against the action of the counterbalance-weights the wind-guards and the 100 slide-bars will accompany it in such movement. When it is desired to swing the sash mentioned on the pins G of its complementary slide-bars B, the wind-guards E of said sash are first raised through the medium of their finger-pieces *f* until they clear the outer edges of the side bars of the sash, when, as 105 110

will be readily observed, the sash may be swung on the pins mentioned. When, however, the sash is returned to the position shown in Fig. 2 relative to the side stiles 5 and the wind-guards E are lowered to their normal positions, the said wind-guards, in addition to excluding the weather, will serve to hold the sash against swinging.

It will be gathered from the foregoing that

- 10 the upper sash is like the lower sash adapted to both slide and swing, the wind-guards appurtenant to the upper sash being raised by hand when the sash is to be swung on its pins G and lowered by hand when the sash is to be 15 secured against swinging movement.

The sashes H H respectively comprise side bars *g*, which are provided in their inner edges with vertical grooves *m* and are also provided with walls *n p* at opposite sides of 20 the said grooves, the walls *p* being more shallow than the walls *n* in about the proportions illustrated, upper end bars *r* having openings *s* in alignment with the grooves *m*, a pane of glass *t*, and glass-holders *u* and wedges *w* for use 25 in connection with the said holders. The pane of glass and the glass-holders are arranged as shown in Fig. 5 precedent to placing the same in the sash. The wedges *w* are then moved downwardly through the openings *s* and between the edges of the pane of glass and the bights of the holders, when, as will be readily observed, the holders will be moved into the grooves *m* of the sashes and secured therein, with the result that casual removal of the 35 glass will be effectually prevented. When, however, it is necessary to replace the pane of glass with a new pane, it is simply necessary to withdraw the wedges and remove the holders, when a new glass may be readily 40 placed in the holders and as readily secured in the sash.

Like the side stiles of the sash-frame the side bars of the sashes are preferably, though not essentially, formed of sheet metal.

45 I have entered into a detailed description of the construction and relative arrangement of the parts comprised in the present and preferred embodiment of my invention in order to impart a definite understanding of the said 50 embodiment. I do not desire, however, to be understood as confining myself to the said specific construction and relative arrangement of parts, as such changes or modifications may be made in practice as fairly fall within the 55 scope of my invention as claimed.

Having described my invention, what I claim, and desire to secure by Letters Patent, is—

1. The combination of a sash-frame having side stiles provided with ways and compartments separated by partition-walls, a sash having grooves in the outer edges of its side bars, vertically and laterally movable wind-guards arranged between the side stiles of the frame and the side bars of the sash and 65 having cams, slide-bars connected and movable vertically with the sash and arranged in the ways of the stiles and provided with means for coacting with the cams of the wind-guards and moving said guards laterally, and counterbalance-weights arranged in the compartments of the side stiles and connected with said slide-bars.

2. The combination of a sash-frame having side stiles provided with ways and compartments separated by partition-walls, a sash having grooves in the outer edges of its side bars, vertically and laterally movable wind-guards arranged between the side stiles of the frame and the side bars of the sash and 75 having cams, vertically-movable slide-bars arranged in the ways of the stiles and having cams complementary to those of the wind-guards, counterbalance-weights arranged in the compartments of the side stiles and connected with the slide-bars, and a connection between the slide-bars and the sash whereby the sash is adapted to swing when the wind-guards are clear of the sash.

3. The combination of a sash-frame, a sash, 90 vertically and laterally movable wind-guards arranged between the frame and the sash and having inclined cams, vertically-movable slide-bars movable in the frame and having cams complementary to those of the wind-guards, 95 means for assisting the upward movement of the slide-bars, and a connection between the slide-bars and the sash whereby the latter is adapted to swing when it is clear of the wind-guards.

4. In a sash, the combination of a frame having grooves in the inner sides of its side bars, and also having openings in its upper end bar in communication with the said grooves, a pane of glass, glass-holders arranged in the grooves of the side bars and receiving opposite edges of the pane of glass, and wedges interposed between the said edges of the glass and the glass-holders.

In testimony whereof I have hereunto set my hand in presence of two subscribing witnesses.

JESSE G. ROSEBOOM.
